UNITED STATES PATENT OFFICE.

EDWARD BELLINGER, OF ROCKY FORD, COLORADO.

SAFETY GAGE-COCK.

1,126,357.

Specification of Letters Patent.

Patented Jan. 26, 1915.

Application filed May 20, 1914. Serial No. 839,813.

To all whom it may concern:

Be it known that I, EDWARD BELLINGER, a citizen of the United States, residing at Rocky Ford, in the county of Otero and State of Colorado, have invented new and useful Improvements in Safety Gage-Cocks, of which the following is a specification.

This invention relates to safety gage 10 cocks, the object of the invention being to provide a gage cock which will automatically cut off the pressure in case the gage glass breaks.

A further object of the invention is to 15 provide in connection with a gage cock of the class referred to, a hand controlled valve by means of which the pressure may be cut off independently of the automatic check valve and by means of which also said automatic check valve may be displaced so as 20 to open up communication with the gage glass for blowing the latter out.

With the above and other objects in view, the invention consists in the novel construction, combination and arrangement of parts, 25 as will be hereinafter more fully described, illustrated and claimed.

The accompanying drawing represents partly in elevation and partly in longitudinal section a safety gage cock embodying 30 the present invention.

Referring to the drawings A designates the body of the gage cock, the same being provided with a valve chamber 1 extending 35 longitudinally of one end of the body, and a pressure inlet passage 2 extending longitudinally of the other end of the body. The valve chamber 1 and the pressure inlet passage 2 are connected by means of an intermediate passage 3 which extends obliquely 40 in relation to the chamber 1 and passage 2 and in which is arranged an automatic check valve 4 shown in the form of a ball. The passage 3 extends on both sides of 45 the adjacent end of the passage 2 and the outer end portion of the intermediate passage 3 is internally threaded to receive the threaded shank 5 of an adjustable valve support 6 against which the valve 4 is 50 adapted to rest when out of its working position. The valve support 6 is provided at its outer end with a head 7 to provide for adjusting the same. At its inner end the intermediate passage 3 communicates with 55 the inner end of the valve chamber 1 by means of a small opening 8 which termi-

nates at its opposite ends in valve seats 9 and 10, the last named seat being provided for the automatic check valve 4.

The seat 9 is provided for a cone-shaped valve 11 on the inner end of a valve stem 12 which is threaded at 13 through the end of the valve body 1, the stem also passing through a stuffing box or gland 14 and being provided at its outer end with a handle or wheel 15 by means of which it may be turned. The valve 11 is provided with a displacement pin 16 extending from its smaller end and adapted to pass through the opening 8 and come in contact with the automatic check valve 4 for the purpose of displacing the latter from its seat and thereby allowing the pressure to flow through the passages 2 and 3 and into the valve chamber 1 which is always in open communication with the gage glass shown at 17, the latter being fitted to the body A by means of a gland 18. In case the gage glass should break, the automatic check valve 4 will be immediately seated by means of the pressure behind it and will thereby instantly cut off communication with the valve chamber 1. The operator may then screw the valve 11 tightly against its seat 9 until a repair has been made.

Two of the gage cocks are shown in the drawing, one at the top and the other at the bottom of the gage glass 17. Both of the gage cocks are the same in construction and operation as hereinabove described and shown in the upper sectional part of the drawing.

What I claim is:—

1. In a safety gage cock, a body formed with a pressure inlet passage extending longitudinally of one end of said body, a valve chamber extending longitudinally of the other end of said body and in open communication with the gage glass, and an intermediate passage connecting said longitudinal passages and extending obliquely in relation thereto, a pressure seated check valve movable longitudinally of said intermediate passage and adapted to cut off communication between said intermediate passage and said valve chamber, and a hand operated valve in said valve chamber adapted to cut off communication between said chamber and intermediate passage and provided with a displacement pin adapted to extend into said intermediate passage and unseat said check valve.

2. In a safety gage cock, a body formed with a pressure inlet passage extending longitudinally of one end of said body, a valve chamber extending longitudinally of the 5 other end of said body and in open communication with the gage glass, and an intermediate passage connecting said longitudinal passages and extending obliquely in relation thereto, a pressure seated check 10 valve movable longitudinally of said intermediate passage and adapted to cut off communication between said intermediate passage and said valve chamber, a hand operated valve in said valve chamber adapted

to cut off communication between said 15 chamber and intermediate passage and provided with a displacement pin adapted to extend into said intermediate passage and unseat said check valve, and an adjustable support for said check valve when in non- 20 checking position.

In testimony whereof I affix my signature in presence of two witnesses.

EDWARD BELLINGER.
